UNITED STATES PATENT OFFICE.

GUY W. NELSON, OF BOSTON, MASSACHUSETTS.

STUDDDED APRON.

1,119,860.

Specification of Letters Patent.

Patented Dec. 8, 1914.

Application filed April 23, 1914. Serial No. 833,878.

To all whom it may concern:

Be it known that I, GUY W. NELSON, a citizen of the United States, and resident of Boston, in the county of Suffolk and State of Massachusetts, have invented certain new and useful Improvements in Studded Aprons, of which the following is a specification.

My invention relates to devices for protecting the person and clothing of workmen and has particular reference to a novel leather apron.

In manufacturing plants, particularly in foundries where workmen handle castings or pieces of metal of irregular shape and rough or unfinished exteriors, the wear on the clothing of the workman is considerable. This is particularly true in the operations of grinding rough castings on an emery wheel when considerable force must be exerted by the workman against the article in pressing the same against the emery wheel. Leather aprons have been employed for reducing this wear but even this material becomes worn rapidly by abrasion.

It is an object of my invention to provide an apron which shall protect the clothing of the wearer in an efficient manner and which shall be of sufficient rigidity to lessen the discomfort when pressing the body against an irregular or sharp object. This result is secured in an apron composed of a plurality of thicknesses of sole leather rigidly secured together and provided with a large number of projecting metallic studs. The metal of which these studs is composed is preferably steel, copper having been found to be too soft and easily worn.

The invention will be more readily understood by reference to the accompanying drawings, wherein,

Figure 1 is an elevation of an apron constructed in accordance with my invention, and, Fig. 2 is a section on the line 2—2 of Fig. 1.

Referring more particularly to the drawings it will be seen that I provide a section 10, of sole leather, curved in the arc of a circle, to the other face of which is secured a second thickness 11, of sole leather. The two sections of leather are separated at their marginal edges by means of straps 12, 13, provided with suitable buckles 14, and a

strap 15, provided with a buckle 16. The first mentioned straps are adapted to pass over opposite shoulders, down the back and under the arms of the wearer the last mentioned strap being adapted to pass around the waist of the wearer. One end of each of the straps 12, 13, extends downwardly between the sections 10, 11, of the leather as indicated at 17, 18, and serves to space the sections of leather at points intermediate their edges. The spaces between adjacent sections of leather is provided in order to accommodate the heads 19, of rivets or studs 20, the heads 21 of which project from the outer surface of the section 11 of leather. These studs being placed in close relation to each other form a substantially continuous bearing surface for an object pressed thereagainst, the wear or abrasion being taken by the studs and not by the leather composing the apron. By means of such construction the clothing of the wearer is protected and due to the stiffness of the article the body of the wearer is protected against sharp or angular portions of the object being handled.

I claim:

1. In an apron, the combination of a plurality of sections of leather superposed in spaced relation, and studs mounted in the outer section, said studs having heads located in spaces between said sections, substantially as described.

2. In an apron, the combination of a plurality of sections of leather superposed in spaced relation, hard metal rivets mounted in the outer section, said rivets having heads located in the space between adjacent sections, and straps for securing said apron to the person of a user, substantially as described.

3. In an apron, the combination of a plurality of thicknesses of leather, hard metal studs projecting through the outer thickness of leather, a pair of straps extending upwardly from the apron, each strap being adapted to pass over a shoulder and downward under an arm of a wearer, and an additional strap adapted to pass around the body of the wearer, substantially as described.

4. In an apron, the combination of a plurality of thicknesses of leather, hard metal

studs projecting through the outer thickness of leather, a pair of straps extending upwardly from the apron, each strap being adapted to pass over a shoulder and downward under an arm of a wearer, and an additional strap adapted to pass around the body of the wearer, the end portions of said

straps acting to space apart the thicknesses of leather, substantially as described.

GUY W. NELSON.
